FILLING AND CLOSING MACHINE

Leonard McGihon, San Leandro, Calif., assignor
to King Sales & Engineering Co., San Fran-
cisco, Calif.

Application November 22, 1947, Serial No. 787,502

3 Claims. (Cl. 226—75)

1

The present invention relates to filling and closing machines and is concerned more particularly with an improved machine of this character which is useful in connection with large size containers such as gallon cans, for example.

It is a general object of the invention to provide an improved filling and closing machine.

Another object of the invention is to provide a machine of the above character in which the cans or other containers are carried past respective filling, lid depositing and lid seaming stations in an automatic fashion with a timed control of the operation of the mechanisms at the various stations.

A further object of the invention is to provide a machine of the above character in which the lid seaming mechanism is independently driven in cyclic fashion in time with the operation of the other parts of the machine.

Another object of the invention is to provide a machine of the above character having an improved mechanism for depositing lids on the cans.

Other objects and advantages of the invention will be apparent from the following description of a preferred embodiment thereof, as disclosed in the accompanying drawings, in which:

Figure 1 is a side elevational view of a filling and closing machine embodying the invention.

Figure 2 is a sectional plan view of the machine taken as indicated by the line 2—2 in Figure 1.

Figure 3 is a longitudinal sectional view taken as indicated by the line 3—3 in Figure 2.

Figure 4 is a transverse sectional view taken as indicated by the line 4—4 in Figure 2.

Figure 5 is a fragmentary sectional view of the can lift mechanism and the drive therefor as indicated by the line 5—5 in Figure 4.

Figure 6 is a fragmentary sectional view of a portion of the drive means for the feed conveyor as indicated by the line 6—6 in Figure 4.

Figure 7 is a fragmentary sectional view of a portion of the drive means for the discharge conveyor taken as indicated by the line 7—7 in Figure 4.

Figure 8 is a detail sectional view of the lift mechanism and the conveyor drive taken as indicated by the line 8—8 in Figure 5.

Figure 9 is a sectional elevational view of the conveyor mechanism taken as indicated by the line 9—9 in Figure 2.

Figure 10 is a detail view of the Geneva drive mechanism taken as indicated by the line 10—10 in Figure 3.

Figure 11 is a detail view of the belt tightener construction taken as indicated by the line 11—11 in Figure 9.

2

Figure 12 is an enlarged sectional elevation of one of the lid depositing structures.

General description

Referring to Figures 1 and 2, the filling and closing machine includes a box type frame or body 10 of cast construction and supported at its four corners by legs 11. The upper portion of the frame 10 has secured thereon a sheet metal cover 10a which provides a circular can-way 12 which leads from a feed conveyor 13 to a discharge conveyor 14. The can-way 12 extends past a filling station 15, a lid depositing station 16, and a lid seaming station 17. The cans are fed in intermittent fashion past these stations by a feed turret 18, which is driven in step-by-step fashion as later described, to move cans successively from one station to the succeeding station and which dwells with cans at the respective stations for a period during which the various filling, lid depositing and lid seaming operations are performed at the various stations.

Drive mechanism

Referring to Figure 3, the drive means of the machine includes an electric motor 21 which is mounted on an internal ledge 22 of the frame casting 10 and which is connected by a suitable chain and sprocket drive 23 with a transverse drive shaft 24 (Figures 3 and 4) journaled in opposite bosses 26 of the frame 10. The various instrumentalities for feeding of cans through the machine and for lifting of the cans at certain of the stations into operative engagement are driven from the drive shaft 24.

To effect the intermittent drive of the feed turret 18, the shaft 24 (Figure 3) carries a bevel gear 25 which meshes with a bevel gear 36 journaled on a stub shaft 27 secured in a boss 28 of the frame 10 in a convenient fashion. The bevel gear 36 carries a drive disk 31 (Figures 3 and 10) of a Geneva mechanism including a Geneva gear 32 secured at the lower end of the vertical drive and support shaft 33 for the feed turret 18. The usual Geneva drive roller 34 is mounted upon the drive disk 31 for cooperation with the four slots of the Geneva gear 32. Preferably the Geneva gear 32 is secured to the shaft 33 through a slotted adjusting collar 36 so that appropriate timing adjustment can be made at this point.

The turret 18 (Figures 2 and 3) carries four bell crank feed arms 37, each pivoted thereon by a stud 38 and urged by a spring 39 against a stop 40. The projecting arms of the bell cranks 37 are curved to conform to the contour of the can

being fed around the can-way 12 by the feed turret 18.

From the above description it will be seen that the feed turret 18 receives an intermittent step-by-step movement so that during each step of movement a can will be carried through a path corresponding to one-fourth revolution of the turret. Also a dwell is provided between successive movements of the turret in operative aligned relation with the respective operating stations.

Conveyor mechanisms.

The respective feed and discharge conveyors 13 and 14 (Figures 1, 2, 3 and 9) are similar and are similarly mounted with respect to the frame of the machine.

The feed conveyor 13 comprises a belt trained about respectively driving, and idler drums 41 and 42. The upper stretch of the belt is carried by a flanged plate 43. The driving drum 41 is journalled about a support shaft 44 (Figure 8) secured in a boss 45 of the frame. The driving drum 41 is disposed within the frame 10 and the belt 13 enters the frame through a slot 46 in the upper wall thereof and leaves the frame through a slot 47 in the side wall thereof.

The drive for the driving drum 41 (Figures 4 and 6) includes a sprocket 48 thereon which is engaged by a chain 49 which is trained about an idler sprocket 50 on a stub shaft 51 carried by a bracket 52 pivoted on the drive shaft 24. A drive sprocket 53 on the shaft 24 (Figure 6) engages a chain to impart a counterclockwise rotation to the sprocket 48 and the driving drum 41 as viewed in Figures 5 and 6.

At its outer end the feed belt 13 is trained about the idler drum 42 which is journalled on a suitable shaft supported in respective bearings 57 carried by a belt tightener screw 58 (Figures 2 and 11) which carries a nut 59 engaging the end of a support pipe 61 which extends along side the conveyor 13 and at its other end is supported in a boss 62 of the frame. Preferably, the respective pipes 61 at either side of the belt 13 are connected to a center support standard 63 (Figures 1 and 9) which supports the outer end of both the feed belt 13 and discharge belt 14. The support plate 43 for the feed belt 13 is mounted on the frame casting 10 and the standard 63.

The discharge belt 14 is similar in its construction and mounting to the feed belt 13 and differs only in the arrangement of the drive parts. Referring to Figure 7, it will be seen that the drive sprocket 48a, the idler sprocket 50a and the drive sprocket 53a for the discharge conveyor or belt are in a different arrangement by virtue of a reverse mounting of the bracket 52a. The drive sprocket 53a is effective with respect to the inside of the chain 49a and as a result drives the drum 41a and its sprocket 48a in a clockwise direction as viewed in Figure 7.

From the above description it is seen that the respective feed and discharge conveyors 13 and 14 are arranged and driven to feed cans to the entrance of the can-way 15 and to receive and remove cans from the exit thereof.

As seen in Figures 2 and 5, the belt 13 is in alignment with the cover sheet 10a of the base 10 so that the cans slide without interruption from the belt onto the can-way 12, which is partially overlapped by the belt 13. The cans are guided inwardly toward the turret 18 by

a yieldable guide rail 66 (Figure 2) pivoted at 67 on the frame 10 and urged counterclockwise by the spring 68. The yieldable guide rail 66 is generally V-shaped and has its outer end held against movement inwardly by the circular guide rail 69 suitably secured on the frame of the machine to form the outer wall of the can-way 12. The nose of the V-shape is provided by a roller 66a. Cans such as indicated at 71 in Figure 2 as they are moved onto the can-way by the belt 13 are guided inwardly by the yieldable rail 66 to engage the feed turret 18 for pick-up by one of its feed arms or bell cranks 37. By virtue of the V-construction of the rail 66 a can which is not sufficiently advanced at the moment of engagement by an arm 37 is forced backwardly along the conveyor 13, while a can that has passed the point of the V is engaged with the arm 37 and travels around with it past the various processing stations. If a can has a straight line or direct engagement with the roller 66a of the V, the rail 66 yields to allow the can to shift to either side of the nose.

Filling station

The filling station comprises a suitable form of tank 76 secured on a pair of parallel cross angles 77 which are supported at one side by an upstanding bracket 78 from the table 10 and at the opposite side by a similar bracket 79. Associated with the filling tank 76 is a conventional form of spring-urged filling valve including a spring-urged head 80 and a valve 81. Any suitable form of valve which opens in response to lifting the can may be employed.

To effect lifting of the can, a can lift plate 82 (Figure 4 and 5) is mounted at the upper end of a lift shaft 83 slidably journalled in a boss 84 of the frame 10 and carrying at its lower end an adjusting screw 86 engaged with a roller 87 at one end of a bell crank 88 pivoted at 89 on the frame 10. The other end of the bell crank 88 has a roller 91 engaging a cam 92 secured on the drive shaft 24 by means of an adjustable coupling plate 93. The rise of the cam 92 is such that the plate 83 is in its upper position as shown for the major portion of the dwell between each movement of the turret 18, being lifted at the beginning of a dwell and being lowered just before the end of the dwell.

Thus a can on the lift plate 82, as shown in Figure 4, will be engaged with the filling valve and filled to the desired head space at the filling station.

Lid depositing station

The lid depositing means includes a support bracket 96 (Figures 1, 2, 3 and 12) which has a plurality of bosses 97 engaging below the cross angles 77 and secured thereto by suitable bolts. The bracket 96, as seen in Figure 1, extends to one side of the cross angles 77 to a position overlying the can-way at the lid depositing station 16. The bracket 96 is apertured at 98 (Figures 2 and 3) at the station 16 and carries four posts 101 about the aperture 98. The posts 101 are spaced to be tangent to a stack of lids 102 in vertical alignment with a can 71 at the lid depositing station. The stack of lids 102 are supported on a pair of opposite lid support and control elements 103 having their respective bosses 104 secured on respective support and operating shafts 106 mounted in the bosses 107 of the frame bracket 96. Each element 103 comprises a pair

of axially offset disk segments 103a and 103b. The knife-edge disk segments 103a normally support the stack of lids, while the auxiliary stack supporting segment 103b is spaced vertically with respect to the disk segment 103a to accommodate one lid between the segments and serves to separate the lowermost lid from the remainder of the stack upon depositing of the lowermost lid. Each of the support shafts 106 and the disk segments 103 thereon are under the influence of a spring 109, the leftmost assembly in Figure 2 being urged counterclockwise and the rightmost assembly being urged clockwise. The stop arms 110 in the respective bosses engage a rib 96a to limit this spring urged movement.

The shafts 106 of the disk assemblies carry respective operating arms 111 (Figures 2 and 3). The stop position of these support disk assemblies places the operating arms 111 therefor in the path of a can being moved into the lid depositing station and provides can operated means for oscillating the respective disk segments 103 to first move the disk segments 103b into supporting relation with the stack of lids immediately above the lowermost lid and to thereafter move the disk segments 103a out of supporting relation with the lowermost lid 102 so that it will fall on a can aligned therewith upon the completion of the forward movement of the disk assemblies. At such time the disk segments 103a remain out of supporting relation with respect to the stack of lids. Upon the return movement of the disk assemblies, the disk segments 103a are moved back into supporting relation with respect to the stack of lids and thereafter the disk segments 103b are moved out of supporting relation therewith to drop the stack on the disk segments 103a ready for another lid depositing operation.

With some products it is desirable to provide an oxygen free inert atmosphere within the can, and for this purpose a pipe 116 (Figures 1, 2 and 3) is provided adjacent the lid depositing station having apertures disposed to direct an oxygen-free gas into the top of the can just before the lid is deposited. The pipe 116 is supported at its lowermost end from a valve 117 having valve operating fingers 118 (Figure 2) disposed in the path of rollers 119 carried by the pivot studs 38 of the can advancing fingers or arms 37. The valve 117 is connected to a suitable source of oxygen-free atmosphere such as nitrogen, for example, and the relation of the rollers 119 and the arm 118 are such that the valve is opened to inject the nitrogen just ahead of the time for deposit of the lid on the can.

Lid seaming mechanism

At the lid seaming station 17 (Figures 1, 2 and 4) there is provided a lid seamer 121 of conventional construction provided with a cyclic drive including an electric motor 122 and a drive control arm 123. The body of the lid seamer is mounted on the bracket 79 and is provided with a centering chuck 124 and seaming rollers 126, all of conventional construction. The lid seamer 121 is aligned with the lifter 127 which is identical in all respects to the lift mechanism associated with the filling station. The lift bell crank 88a (Figure 7) for the lift plate 127 provides an offset lever arm to apply pressure to the can during the seaming operation and in effect supplies a yieldable or resilient pressure means.

The lid seamer, as stated above, is of the cyclic operable type and its operation is timed to occur during the dwell between the advance of the cans

and for this purpose its control arm 123 is connected by a link 131 with an arm 132 secured at the upper end of a shaft 133. The lower end of the shaft 133 (Figure 3) carries an arm 134 (Figure 10) which is disposed in the path of a cam segment 136 carried by the drive disk 31 of the Geneva mechanism. The cam segment 136 initiates the cycle of operation of the seaming mechanism at about the time the can has been lifted to engage the lid thereon with the can chuck as shown in Figure 4. The cycle of operation of the seamer continues until the can chuck 124 has been rotated a sufficient number of times to perform the lid seaming operation. When the cycle is completed the seaming rollers remain in inactive position until a seaming cycle is again started by the cam 136.

Operation

The operation of the machine may be briefly summarized as follows: The cans to be filled and closed are placed on the feed conveyor 13, for example, as shown in dotted lines in Figure 2, and they are carried by the conveyor 13 against the yieldable guide rail 66. The V-shape construction of the guide rails 66 directs a can in towards the feed turret 18 for engagement by one of the yieldable feed arms 31.

As previously explained, the feed arms 31 and the turret 18 are driven one-quarter revolution at a time in intermittent fashion so that a can engaged with the feed arm 31 will be carried successively through the filling station 15, the lid depositing station 16 and the seaming station 17. As a can is fed onto the can lift plate 82 at the filling station it is aligned with the spring-urged head 80 of the filling structure and upon lifting of the plate 82 the can is engaged with the head 80 and moves it upwardly to open the valve so that the material being filled will flow into the can up to the desired head space in the can.

The above operation occurs during the dwell in the movement of the feed turret 18.

Upon the next step of movement of the feed turret 18 a can filled at the filling station is carried to the lid depositing station and placed in alignment with the lid depositing structure, as shown in Figures 2 and 3. As the can enters this station it engages the operating arms 111 so that the support disk segments 103a and 103b at either side are oscillated to first engage the segments 103a below the next lowermost lid of the stack and then to remove the support of the segments 103b from the lowermost lid so that it will drop upon the can. Just before the lid falls on the can the valve 117 is operated so that gas from the pipe 116 is blown into the head space of the can to substantially displace the air therein.

Upon the next step of movement of the feed turret 18 the filled can with the lid thereon is moved to the seaming station onto the lift plate or lifter 127 in alignment with the centering chuck 124 (Figure 4) of the lid seamer. At the beginning of the dwell between successive steps of movement of the cans the lid seamer has its operation started through the linkage 132-131 and the cam 136, and the can is lifted until the chuck 124 engages the lid and through its engagement with the lid rotates the lid and the can with respect to the seaming rollers 126. The conventional lid seaming operation is then performed and completed before the lifter 127 is lowered and the turret again operated so that the closed can is moved onto the discharge conveyor 14.

While I have shown and described certain preferred embodiments of the invention, it is apparent that the invention is capable of variation and modification from the forms shown so that its scope should be limited only by the scope of the claims appended hereto.

I claim:

1. In a can filling and closing machine, a filling station including a filling valve, a lid station including a lid feeder, a closing station including a cyclically operable lid seamer and normally inactive drive means therefor, a turret having a series of can supports for travelling successively through said stations, means for effecting an intermittent drive of said turret to provide successive dwells in the motion thereof with one of said can supports at each of said stations, and means for initiating operation of said valve, said lid feeder and said lid seamer during each dwell in the movement of said turret, said lid seamer being timed in its operation to complete a lid seaming operation during one of said dwells in the movement of said turret.

2. In a can filling and closing machine, a filling station including a filling valve, a lid station including a lid feeder, a closing station including a cyclically operable lid seamer and normally inactive drive means therefor, a can support for travelling successively through said stations, means for effecting an intermittent drive of said can support to provide successive dwells in the motion thereof with said can support at each of said stations, and means for initiating operation of said valve, said lid feeder and said lid seamer during each dwell in the movement of said can support, said lid seamer being timed in its operation to complete a lid seaming opera-

tion during one of said dwells in the movement of said can support.

3. In a filling and closing machine, a fixed filling station including a filling valve, a fixed lid station including a lid feeder, a fixed closing station including a lid seamer, a fixed arcuate can-way for supporting cans for movement past the respective stations, a rotatable turret having a series of spring thrust radially extending members for engaging the sides of the respective cans and moving them along said can-way while supported by said can-way, means for effecting intermittent drive of said turret to provide successive dwells in the motion thereof with one of said can engaging members at each of said stations, and means for initiating operation of said valve, said lid feeder and said lid seamer during each dwell in the movement of said turret.

LEONARD MCGIHON.
